US00D909819S

(12) **United States Design Patent** (10) Patent No.: **US D909,819 S**
(45) Date of Patent: **** Feb. 9, 2021**

- (54) **BOWL**
(71) Applicant: **YETI Coolers, LLC**, Austin, TX (US)
(72) Inventors: **Kyle Ellison**, Austin, TX (US); **Dustin Bullock**, Austin, TX (US); **Colin Darling**, Austin, TX (US)
(73) Assignee: **YETI Coolers, LLC**, Austin, TX (US)
(**) Term: **15 Years**
(21) Appl. No.: **29/716,338**
(22) Filed: **Dec. 9, 2019**

Related U.S. Application Data

- (63) Continuation of application No. 29/658,678, filed on Aug. 1, 2018, now Pat. No. Des. 871,159.
(51) LOC (13) Cl. **07-01**
(52) U.S. Cl. **USPC D7/587**
(58) **Field of Classification Search**
USPC D7/500, 587, 565, 560, 543, 584;
D30/130
CPC A47G 19/025; A47G 19/02

(57) **CLAIM**

The ornamental design for a bowl, as shown and described.

DESCRIPTION

FIG. 1 is a top, front, right perspective view of a first embodiment of a bowl showing our new design;

FIG. 2 is a front view thereof, wherein the rear view is a mirror image of FIG. 2;
 FIG. 3 is a right side view thereof, wherein the left side view is a mirror image of FIG. 3;
 FIG. 4 is a top view thereof;
 FIG. 5 is a bottom view thereof;
 FIG. 6 is a top, front, right perspective view of a second embodiment of the bowl of FIGS. 1-5 showing our new design;
 FIG. 7 is a front view thereof, wherein the rear view is a mirror image;
 FIG. 8 is a right side view thereof, wherein the left side view is a mirror image;
 FIG. 9 is a top view thereof;
 FIG. 10 is a bottom view thereof;
 FIG. 11 is a top, front, right perspective view of a third embodiment of the bowl of FIGS. 1-5 showing our new design;
 FIG. 12 is a front view thereof, wherein the rear view is a mirror image;
 FIG. 13 is a right side view thereof, wherein the left side view is a mirror image;
 FIG. 14 is a top view thereof;
 FIG. 15 is a bottom view thereof;
 FIG. 16 is a top, front, right perspective view of a fourth embodiment of the bowl of FIGS. 1-5 showing our new design;
 FIG. 17 is a front view thereof, wherein the rear view is a mirror image;
 FIG. 18 is a right side view thereof, wherein the left side view is a mirror image;
 FIG. 19 is a top view thereof; and,
 FIG. 20 is a bottom view thereof.
 The broken lines depicting the remainder of the bowl show features that form no part of the claimed design. The contrast in shading represents a contrast in appearance.
